UNITED STATES PATENT OFFICE.

CLARENCE W. COLEMAN, DECEASED, LATE OF WESTFIELD, NEW JERSEY, BY KATHARINE COLEMAN, ADMINISTRATRIX, OF WESTFIELD, NEW JERSEY, ASSIGNOR, BY MESNE ASSIGNMENTS, TO HALL SWITCH & SIGNAL COMPANY, OF NEW YORK, N. Y., A CORPORATION OF MAINE.

RELAY.

1,174,230.

specification of Letters Patent.

Patented Mar. 7, 1916.

Original application filed May 7, 1909, Serial No. 494,665. Divided and this application filed January 16, 1911. Serial No. 602,911.

To all whom it may concern:

Be it known that CLARENCE W. COLEMAN, deceased, late of Westfield, county of Union, State of New Jersey, did invent certain new and useful Improvements in Relays, of which the following is a specification.

The invention relates to relays, and more particularly to relays operated by a pulsating or alternating current.

10 The object of the invention is to provide a simple and efficient relay of the vibratory reed type which may be utilized as a selective relay; this application being a division of a former application for railway signaling systems, filed May 7th, 1909, Serial No. 494665.

The invention involves the provision of a relay so constructed that it will be actuated to maintain its circuit closed when, and only 20 when, the current in its coil is of a definite frequency. The relay may have but a single winding which may be connected directly to any suitable source of pulsating or alternating current, but in either case the selective 25 action is not dependent upon any apparatus external to the relay itself. Specifically the inventor provided as the armature of the relay a vibratory permanently magnetized reed which will be caused to vibrate by the field 30 magnet of the relay only when the field is energized by a current of a frequency corresponding substantially to the natural period of vibration of the reed, and caused the continued vibration of the reed to maintain the 35 closure of a circuit which is independent of the reed. This is effected by causing the contact actuated by the reed to be sluggish in its movement, as by being connected to a dash-pot. Thus the inventor obtained the selective 40 action of such a vibratory reed armature without the intermittent closure of any circuit with the obvious disadvantages accompanying the same.

The invention will be best understood by 45 the following description, taken in connection with the accompanying drawings, in which—

Figure 1 is a side elevation of the preferred form of the relay; Fig. 2 is a plan view of the same; Fig. 3 is a side elevation 50 of a modification; and Fig. 4 is a plan view of the same.

Referring to the drawings, Fig. 1, 1 is a

relay coil having a soft iron core 2, preferably secured to one end of a base plate 3, in the form of a permanent magnet which is 55 provided with standards 4 and 5 at each end forming part of the magnetic circuit. Upon the standard 4 is secured a projection 6, having a bifurcated vertical shoulder 7 provided with a longitudinally adjustable screw 8, 60 adjusted by means of a nut 9. A vibratory armature 10, in the form of a steel reed, completes the magnetic circuit and is detachably secured at its rear end to the screw 8, so that the armature may be moved back and forth 65 over the core of the magnet by manipulating nut 9.

The standard 4 preferably has its top surface cored out, as shown, to provide shoulders 11 and 12, upon which the armature 10 70 rests. The upper surface of these shoulders should be substantially in the same horizontal plane with the center of the screw 8, so that the armature will rest easily upon both. The standard 4 is provided with the cored 75 out cap plate 13, having offset shoulders registering with the shoulders 12 and 13, for firmly gripping the armature 10 down on the standard, so that the vibration of the armature will take place from the outer end 80 of shoulder 11.

A switch 14 preferably formed of resilient metal and having arms 15 and 16, is mounted upon the standard 5 so as to engage an adjustable contact 18, which is mounted in a 85 block of insulating material secured to a vertical extension of the standard. The switch 14 and arms 15 and 16 are also secured to a block of insulating material, which is provided with a pivot pin journaled 90 in the cupped ends of two adjustable screws, as shown.

The extremity of arm 15 is preferably provided with a tip to receive the impulses from armature 10, while the outer end of arm 16 is pivotally connected with one element of a dash-pot 17, the other element of which is secured to a projection from the base-plate. The dash-pot is filled with a liquid, preferably alcohol, and is for the 95 purpose of retarding the movements of switch 14, so that its movements will be too sluggish to allow it to make and break contact in unison with armature 10, as a result of

which the switch will be held in engagement with contact 18 during the vibrations of armature 10.

After the armature has been adjusted by 5 the nut 9 to its supposed proper length, it is gripped tightly upon the shoulders 12 and 13 by screwing down the cap plate, and the coil 1 is energized. If the natural 10 period of vibration of the armature, as adjusted, is in resonance with the period of magnetic vibration set up in the coil, that is, if the natural number of vibrations per unit of time of the armature be the same as the number of cycles per unit of time of the 15 current in the coil, then the armature will respond to the so-called magnetic vibrations set up by the coil, and will vibrate back and forth in unison with the reversals of current in the coil, thus giving a continuous 20 rain of hammer blows upon the end of lever 15, forcing the switch 14 in engagement with contact 18 to close the signal circuit. The switch is held in its closed position by the dash-pot 17, which damps the vibrations 25 of the switch member so as to prevent any possibility of the switch vibrating in unison with the armature 10. If the length of the armature is such that its own period of vibration is substantially different from the 30 magnetic vibration set up in the coil, then the armature will be unable to vibrate with sufficient amplitude to impinge upon the end of lever 15 to close the signal circuit, in which case the cap plate 13 is loosened up 35 and the armature readjusted; after which the cap plate is again tightened up, and so on until the proper adjustment is secured.

Fig. 3 shows a modified form of relay, in which two vibratory armatures are utilized for operating the switch 14, one being mounted at each end of the permanently magnetized base-plate. These vibratory armatures being secured to opposite poles of the permanent magnet, are oppositely 45 polarized, that is, the north pole of one and the south pole of the other are situated over the relay core, so that for each complete magnetic cycle in the core, the switch 14 will receive two blows, one from 50 each armature, while with the single vibratory armature the switch receives but one blow for each magnetic cycle in the core. The operation and adjustment of this relay is the same as that shown in Fig. 3, the only 55 difference in the relays being in the relative position of the parts to accommodate the second vibratory armature.

The standards 4 4' for carrying the vibratory arms, as shown in Fig. 3, are mounted 60 at the ends of the permanently magnetized base-plate, and secured to the same plate adjacent to one of the standards is an upright 19, upon which is pivoted the switch 14, and at the upper end of which is secured 65 the insulated contact 18. A second upright

20 is secured to the base-plate adjacent to the other standard and its upper end carries one member of the dash-pot 17. In this relay it will be seen that the core 2 is mounted at the center of the permanent magnet 70 and that the standards 4 4', upright 19, operating lever 15 and vibrating armatures, complete the magnetic circuit.

One advantage of the two oppositely polarized vibratory armatures over the single 75 armature is that the period between blows upon switch 14 is reduced by half, since the blows are alternately struck by the two armatures, giving a more continuous action 80 and thus preventing switch 14 from vibrating with either of them to make and break its circuit.

Another advantage in the use of two armatures is that the switch will be held 85 closed by the vibrations of one, should the other become broken or otherwise thrown out of order.

Although I have described the improvements in great detail, nevertheless I do not desire to be limited to such details except 90 as clearly pointed out in the appended claims since many changes and modifications may well be made without departing from the spirit and scope of the invention in its broadest aspects.

What I claim as new and desire to secure by Letters Patent, is:

1. In a relay, the combination of a coil to be energized by a suitable source of current, a plurality of oppositely polarized vibratory armatures co-operatively related to said coil, constructed to be operated responsive only to a current in said coil of a substantially predetermined frequency, and a resilient vibratory switch member mounted 105 adjacent said armatures and movable thereby, said switch member constructed to have a slower movement than said armature.

2. In a relay, the combination of a coil, a plurality of oppositely polarized vibratory 110 armatures constructed to be vibratory in synchronism with the current to be used in said coil, and a switch member controlled by the vibrations of said armatures.

3. In a relay, the combination of a coil, 115 a plurality of oppositely polarized armatures constructed to be vibratory in synchronism with the current to be used in said coil, and a switch member operated by the force of a series of impulses from said armatures.

4. In a relay, the combination of a coil, 120 a plurality of oppositely polarized armatures constructed to be vibratory in synchronism with the current to be used in said coil, and a pivoted switch member having a different period of vibration from said armatures arranged to be moved to a given position and there maintained by the vibrations of said armatures.

5. In a relay, the combination of a coil, a permanent magnet, a vibratory reed at each pole of said magnet and coöperatively related to said coil, and a switch member controlled by the vibrations of said reeds.

6. In a relay, the combination of a coil, a permanent magnet, a plurality of oppositely polarized vibrating reeds coöperatively related with said coil and magnet, and a 10 switch member controlled by the vibrations of said reeds.

7. In a relay, the combination of a coil, a permanent magnet, a soft iron core for said coil, a vibratory reed at each pole of 15 said magnet and coöperatively related to said core, and a switch member having a different period of vibration from said reeds and arranged to be moved to a given position and there maintained by the vibrations 20 of said reeds.

8. In a relay, the combination of a polarized magnet comprising a base piece with projections at each end constituting the opposite poles of the magnet, a plurality of 25 vibratory reed armatures one for each projection extending into proximity to each

other at a point between the said projections, means for adjusting the length of the vibratory portion of each reed extending beyond the projections, means for rigidly 30 clamping each reed upon the corresponding projection whereby said reeds are polarized, a soft iron core mounted on the base piece intermediate the projections and extending into proximity to the adjacent extremities 35 of the reeds, a coil on said core for receiving alternating current to vibrate the reeds, contacts, and a member actuated by the vibrations of said reeds and moved into a given position to close the contacts and 40 maintained in said position by said vibrations.

In testimony whereof, I have signed my name to this specification, in the presence of two subscribing witnesses.

KATHARINE COLEMAN,
